Primary Examiner — Philip S Hyder(74) *Attorney, Agent, or Firm* — Steve LeBlanc, LLC(57) **CLAIM**

The ornamental design for a switchblade knife, as shown and described.

DESCRIPTION

FIG. 1 is a blade-end view of the switchblade knife;
 FIG. 2 is a glass break-end view of the switchblade knife;
 FIG. 3 is a left side view of the switchblade knife;
 FIG. 4 is a right side view of the switchblade knife;
 FIG. 5 is a top view of the switchblade knife; and,
 FIG. 6 is a bottom view of the switchblade knife.
 The broken lines depict portions of the switchblade knife in which the design is embodied that are not considered part of the claimed design.
